(57) **CLAIM**

The ornamental design for a beverage system, as shown and described.

DESCRIPTION

FIG. 1 is a front elevation view of my new design for a beverage system, with the lid portion removed for clarity of disclosure;

FIG. 2 is a rear elevation view thereof;

FIG. 3 is a right-side elevation view thereof;

FIG. 4 is a left-side elevation view thereof;

FIG. 5 is a top plan view thereof;

FIG. 6 is a bottom plan view thereof;

FIG. 7 is a top perspective view thereof;

FIG. 8 is a front elevation view of my new design for a beverage system;

FIG. 9 is a rear elevation view thereof;

FIG. 10 is a right-side elevation view thereof;

FIG. 11 is a left-side elevation view thereof;

FIG. 12 is a top plan view thereof;

FIG. 13 is a bottom plan view thereof;

FIG. 14 is a top perspective view thereof;

FIG. 15 is a front elevation view of my new design for a beverage system, with the container portion removed for clarity of disclosure;

FIG. 16 is a rear elevation view thereof;

FIG. 17 is a right-side elevation view thereof;

FIG. 18 is a left-side elevation view thereof;

FIG. 19 is a top plan view thereof;

FIG. 20 is a bottom plan view thereof; and,

FIG. 21 is a top perspective view thereof.

The broken lines in the drawing depict portions of the beverage system that form no part of the claimed design. The dot-dash lines indicate boundaries of the claim and form no part of the claimed design.

1 Claim, 20 Drawing Sheets
